UNITED STATES PATENT OFFICE.

PAUL F. YÜNGLING, OF LOS ANGELES, CALIFORNIA.

ELEVATOR FOR WELL TUBES OR CASINGS.

1,082,786.

Specification of Letters Patent. Patented Dec. 30, 1913.

Application filed September 9, 1912. Serial No. 719,439.

To all whom it may concern:

Be it known that I, PAUL F. YÜNGLING, a citizen of the United States, residing at Los Angeles, in the county of Los Angeles and State of California, have invented certain new and useful Improvements in Elevators for Well Tubes or Casings, of which the following is a specification.

This invention relates to certain new and useful improvements in elevators for well tubes or casings, and has for its object to provide an elevator which is adapted to be placed over a well tube or casing to hold the same while being raised or lowered, the elevator being of such construction that it may be readily attached and detached from the tube or casing.

In the make up of a well casing elevator to accord with my invention there is present a tubular portion or ring that is provided on opposite sides with outward projecting trunnions which are recessed to receive springs and bolts, the interior of the ring having bores of two diameters and an intermediate inclined portion, the ring having associated therewith by means of the spring bolts slideable wedging clamps or slips which carry hooks for engagement with the coupling of the well tube or casing when the elevator is placed over the well tube or casing.

In the accompanying drawings, which illustrate one preferred form of the invention, Figure 1 is a side elevation of a well casing elevator showing the parts in position to be placed over a well tube or casing for engagement therewith. Fig. 2 is a side elevation viewed from a point looking toward the end of one of the trunnions and in this view the bail is broken away. Fig. 3 is a plan view partly in section, the section being taken on the line 3—3 Fig. 1. Fig. 4 is a vertical section showing the well casing elevator in position over a well tube or casing as when placed thereon and prior to the engagement of the wedges or slips with the coupling on the well tube or casing, and Fig. 5 is a vertical section of the well casing elevator showing the same positioned to clamp the well tube or casing with the wedges in engagement with the coupling on the well tube or casing.

Referring to the drawings the well tube

or casing 6 has thereon the usual coupling 7 for connecting another section of pipe there- 55 to, as is common in oil and Artesian wells, and it is with such a tube and coupling that the elevator engages for holding the casing while it is being raised or lowered and when sections of casing or tubing are being added 60 to or separated from the string. The size of the tubing or casing elevator in which my invention is embodied depends upon the size of the tube or casing and the coupling.

The elevator embodies in its make up a 65 one piece or solid ring 8, that is shaped to provide internally circular or cylindrical seats for slips or wedging-clamps, the smaller bore of the ring being of greater diameter than the external diameter of the 70 coupling, so that the ring may be passed over the coupling 7, the upper end of the smaller bore joins an inclined wall 9, such wall extending to the lower edge of a larger bore 10, the upper edge thereof being bevelled. The exterior of the ring 8 on opposite sides has hollow trunnions 11 which are engaged by eyes or loops 12 of a bail 13, that is engaged by the usual casing hook when the well tubing or casing is to be raised or 80 lowered. The trunnions 11 are bored to receive annular nuts 14 and to provide openings for bolts 15 and seats for springs 16, the springs encircling the bolts and by bearing against the nuts and the ring 8, about 85 the openings for the bolts tend to force the bolts outward. The bolts have flat cylindrical heads which are seated in recesses formed in the inner faces of slips or wedging clamps, that engage with the underside 90 of the coupling on the well tube.

The wedging clamps or slips 17 are of similar construction a pair of like clamps being associated with the ring 8 by the bolts 15, 15, and the wedging clamps or slips have 95 their inner faces shaped to provide centrally and oppositely disposed segmental portions and from the vertical edges of the segmental portions the inner faces are slightly beveled, as shown by Fig. 3 of the drawings. The 100 exterior configuration of the wedging clamps or slips 17 corresponds with the interior of the ring 8 against which they are drawn by the spring actuated bolts which effect frictional engagement of the wedging clamps 105 with the interior of the ring, the pressure be-

ing sufficient to maintain the wedging clamps in a raised position as shown by Figs. 1 and 2 of the drawings, and when in a raised position the beveled lower ends of 5 the wedging clamps will bear against the inclined wall 9 of the ring and the exterior inclined portion of the wedging clamps engage the beveled edge of the upper portion of the ring; thus maintaining the wedging 10 clamps by frictional contact with corresponding inclined surfaces. The wedging clamps or slips 17 are slotted for the passage therethrough of the bolts 15 and surrounding the slots are recesses to receive the heads 15 of the bolts. Each of the wedging clamps have preferably in line with the slots to project above the upper edges of the same lugs 19 with transverse apertures for the purpose of connecting thereto hooks 20, 20 which swing inward and are maintained in an inclined position by engagement with the upper inner edges of the wedging clamps, as shown by Figs. 1 and 3 of the drawings.

In the construction in which my invention 25 is embodied it will be noted that when the several parts are associated that there are no separable parts requiring manual manipulation to attach or disconnect the tool from the well tube or casing, the ring being in one 30 piece has the wedging clamps or slips connected to the ring and the hooks are held or carried by the wedging clamps, and these features or parts of my invention may be varied in form and proportion or as to minor 35 details without departure from the principle of the invention or combination as set forth in the claims of this specification.

In operation the bail of the elevator is connected to a hoisting cable, the wedging 40 clamps or slips are moved to extend partially above the ring and the hooks are swung across the opening between the wedging clamps, with the parts so positioned the elevator is placed over the tube or casing and 45 when lowered the hooks will engage the coupling so that the ends of the wedging clamps will be below the coupling, the position being indicated by the slackening of the cable, when draft is applied to the cable upward movement will be imparted to the ring and the wedging clamps will be forced inward to embrace the tube or casing so that 50 the upper edges of the clamps will be under the coupling, when the tube or casing may be hoisted. As the bail is in swinging connection with the ring the elevator may be placed in position when the tube or casing is in other than vertical position. It will 55 also be noted that the elevator may be readily detached by first pushing downward on the bail and then lifting by means of the hooks.

From the foregoing description and by

reference to the accompanying drawings the construction and operation will be readily understood to those skilled in the art and acquainted with well tools and well boring or driving machinery.

I claim:—

1. An elevator for well tubes or casings comprising a one piece ring having hollow trunnions, a bail connected to the trunnions, means maintained in slidable engagement with the ring and spring actuated bolts which are partially housed in the hollow trunnions of the ring and engage with said slidable means and with the ring.

2. An elevator for well tubes or casings comprising a ring having trunnions, a bail connected to the trunnions, coupling engaging means and spring actuated bolts reciprocally maintained by the hollow trunnions for slidably associating the coupling engaging means with the ring.

3. An elevator for well tubes or casings comprising a ring having an inner wall of different diameters on different planes, coupling and tube engaging means which are externally shaped to correspond with the inner wall of the ring, slots through the coupling and tube engaging means, and spring actuated bolts which are partially housed in the ring and extend inward to engage with the coupling and tube engaging means to hold the same in engagement with the ring.

4. In an elevator for well tubes or casings, a bail, a ring having trunnions which are engaged by the bail, wedging clamps having slots therethrough, spring actuated bolts carried by the ring for engagement with the wedging clamps to hold the same in movable engagement with the ring and hooks maintained in swinging engagement with the wedging clamps.

5. In a tubing or casing elevator, a ring having bored trunnions, a bail connected to the trunnions, wedging clamps movably associated with the ring, bolts seated to move longitudinally in the trunnions and to engage the wedging clamps to associate the same in movable relation with the ring.

6. In a tubing or casing elevator, a ring having an internal diameter greater than the tube or casing and provided with trunnions located adjacent to the upper portion of the ring, a bail which engages with the trunnions, wedging clamps maintained in movable engagement with the ring and hooks of rigid material having one end bent to provide a pipe engaging portion the opposite end being pivoted to each of the wedging clamps in such a manner to swing inward and extend toward the opposite wedging clamps.

7. In a tubing or casing elevator a ring

having on opposite sides trunnions, a bail with which the ring is associated by engagement with the trunnions, slidable members associated with the ring to be capable of longitudinal and lateral movement and hooks pivotally attached to and maintained in swinging engagement with the slidable members to extend across the space between

the wedges with the bent ends downward for engagement with the end of a tube.

In testimony whereof I affix my signature in presence of two witnesses.

PAUL F. YÜNGLING.
